INVENTOR
Walter J. O'Neill
BY
W. M. Katz ATTORNEY

UNITED STATES PATENT OFFICE.

WALTER I. O'NEILL, OF NEW YORK, N. Y.

WRENCH.

Application filed December 20, 1924. Serial No. 757,106.

My invention relates to wrenches having adjustable jaws, and especially to the type known as monkey wrenches. It is well known that in the ordinary wrench, especially after it has been worn from use, it is difficult to adjust the jaws to a tight fit upon the nut or other object clamped between them.

It is an object of my invention to provide a wrench which shall have convenient and simple means for producing an additional clamping effect of the jaws after the latter have been adjusted in the usual manner to the member to be operated upon.

In the drawings annexed hereto and which are intended merely as illustrations of my invention, Fig. 1 is an elevation of one embodiment of my invention.

Fig. 2 is a view, looking upwards, of Fig. 1.

In Fig. 1, the shank of the wrench is represented at 1, the lower part of the shank being formed as a handle, and the upper part being provided with a jaw 2. Another jaw 3 is slidably mounted upon shank 1 by means of the sleeve 4, and is adapted to cooperate with jaw 2. Mounted to move along shank 1 is a sleeve 5 bearing a rotatable, screw-threaded shaft mounted in bosses 14, 15 and adapted to engage screw threads 7 in sleeve 4. A knurled nut 8 is provided to facilitate rotation of shaft 6.

Pivottally mounted upon shank 1, as at 9, is a bifurcated, bell crank lever 10 having a grip portion 11 extending downward into proximity with and to one side of the grip portion of the shanks; and a lever arm 12 extending upwardly upon the other side of the shank 1, and carrying a roller 13 adapted to engage the boss 14. A leaf spring 16 interposed between shank 1 and lever grip 11 urges the two latter apart.

In operation the jaws are adjusted as closely as possible by turning the nut 8 in the usual manner. The operator then grasps the members 1 and 11 in his hand thus bringing them together against the action of spring 16.

By this action the roller 13 rises, carrying with it sleeves 5 and 4 and closing the jaws 2 and 3 firmly against the object to be held. The parts are so arranged and designed that the roller 13 is never far from the dead center position thus making it possible to exert any clamping force desired.

The lower part of the shank 1 may be provided, if desired, with a latch to hold lever grip 11 in the dotted line position shown in the drawings. Furthermore the roller 13 may be replaced by a direct link connection to boss 14; or boss 14 may carry roller 13 and the upper part of arm 12 shaped as a cam to cooperate therewith.

My invention may be applied to any of the various types of wrench now in use and is not limited except as specified in the claim. It is obvious that the jaws may be provided with teeth or serrations, or shaped in any manner for special purposes.

I claim:

A wrench comprising a shank having a jaw at one end and a handle at the other end, a jaw movably mounted upon the shank to cooperate with the first mentioned jaw, means for adjusting the second mentioned jaw comprising screw threads formed in the said second mentioned jaw and a screw extending parallel to the shank and engaging the said screw threads, means for moving the adjusting means and second mentioned jaw as a unit comprising a pivot provided on the shank, a lever mounted upon the pivot and having one arm extended in proximity to the handle and other arm in proximity to the adjusting means, and a roller carried by the last named arm in position to actuate the adjusting means, the parts being arranged so that in operative position, the roller and pivot are in a line nearly parallel to the screw.

Signed at New York in the county of New York and State of New York this 18th day of December, A. D. 1924.

WALTER I. O'NEILL.
